ELECTRICAL RELAY

Branko Lazich, Edgewood, and Harry E. Ashworth, Swissvale, Pa., assignors to The Union Switch & Signal Company, Swissvale, Pa., a corporation of Pennsylvania

Application February 19, 1931, Serial No. 516,934

15 Claims. (Cl. 175—320)

Our invention relates to electrical relays. We will describe one form of electrical relay embodying our invention, and will then point out the novel features thereof in claims.

5 The accompanying drawing is a diagrammatic view illustrating one form of relay embodying our invention.

Referring to the drawing, the reference character A designates an electromagnet which, in 10 the form here shown, comprises three magnetizable cores 1, 2 and 3 connected together at their upper ends by a backstrap 4, and provided at their lower ends with enlarged pole pieces 1^a, 2^a and 3^a, respectively. The cores 1 and 2 are 15 provided with energizing windings 5 and 6, respectively, while the core 3 is provided with a closed conducting member, here shown as a sleeve 7 of suitable material, such as copper. The pole piece 3^a is bifurcated, and pivotally 20 supported between the bifurcations of this pole piece for swinging motion toward one or the other of the pole pieces 1^a or 2^a, is a magnetizable armature 8. Attached to the underside of armature 8 by means of suitable insulating supports 9 are two contact fingers 10 and 11. When 25 armature 8 is swung toward pole piece 2^a, as shown in the drawing, contact finger 10 engages a fixed front contact member 10^a to close a contact 10—10^a, and contact finger 11 engages a 30 fixed contact member 11^b to close a contact 11—11^b. When armature 7 is swung toward pole piece 1^a, however, contact finger 10 then engages a fixed contact member 10^b to close a contact 10—10^b, while contact finger 11 engages a fixed 35 contact member 11^a to close a contact 11—11^a.

The windings 5 and 6 are connected in series, and are supplied with current from a suitable source of energy, here shown as a battery 12. It will be seen from an inspection of the drawing, however, that when contact 11—11^b is closed, as illustrated in the drawing, winding 6 is short-circuited, and that when contact 11—11^a is closed, winding 5 is short-circuited. The windings 5 and 6 are so arranged that the fluxes 45 which are set up in core 3 by currents in these windings, thread core 3 in the same direction. The supply of current to the windings 5 and 6 may be controlled in any suitable manner, as by a manually operable switch 13.

50 The portion of the relay thus far described is well known, and its operation is as follows: As shown in the drawing, switch 13 is open and armature 7 is swung toward pole piece 2^a, so that contacts 10—10^a and 11—11^b are closed. If, now, switch 13 is closed, current flows through wind-

ing 5, but since contact 11—11^b is closed, winding 6 is short-circuited, and winding 6 therefore remains deenergized. The energization of winding 5 sets up a flux in core 1 which causes armature 8 to swing toward pole piece 1^a. During this motion of the armature, contacts 10—10^a and 11—11^b become opened, and contacts 10—10^b and 11—11^a become closed. The closing of contact 11—11^a short-circuits winding 5, and the field set up by this winding commences to decay. Due, 60 however, to the short-circuited winding and to the sleeve 7 on core 3, this decay is comparatively slow. The opening of contact 11—11^b meantime has allowed winding 6 to become energized. The growth of the flux set up in core 2 by this latter 65 winding is likewise comparatively slow due to sleeve 7 on core 3, but after an interval of time, the torque exerted on armature 8 by this flux overbalances the torque exerted on armature 8 by the decaying flux in core 1, and armature 8 70 then swings back toward pole piece 2^a. This motion first opens contacts 10—10^b and 11—11^a and then closes contacts 10—10^a and 11—11^b. The field of winding 5 then slowly builds up and the field of winding 6 slowly decays, the building 75 up of the field of winding 5 being retarded by sleeve 7, and the decay of the field of winding 6 being retarded both by sleeve 7, and by the self-inductance of the short-circuited winding 6. Eventually, the torque exerted by the decaying 80 flux in winding 6 will not be sufficient to hold the armature, and the armature will then again swing toward pole piece 1^a. It will be apparent, therefore, that armature 8 is swung to and fro as long as switch 13 is closed, and it will also be 85 apparent that a considerable interval of time elapses between successive armature movements.

In a relay of the type described, it is sometimes desirable to vary the interval of time which elapses between successive armature movements. 90 We have found that this may be done by supplying core 3 with an additional flux; the time interval which elapses between armature movements being increased as the strength of this additional flux is increased when the additional 100 flux threads core 3 in the same direction as the resultant flux in the core due to the current supplied to windings 5 and 6, and being decreased as the strength of the additional flux is increased when the additional flux threads core 3 in the 105 opposite direction from the resultant flux in core 3 due to the current supplied to windings 5 and 6. One way in which the additional flux may be supplied to core 3 is to apply a magnetomotive force to the core, and the means here shown for 110

- doing this comprises a winding 14 which surrounds the core and which is at times supplied with current from battery 12. The supply of current to winding 14 may be controlled in any suitable manner such as by a manually operable switch 15, and a variable resistor 16 or other suitable means may be connected in series with the winding to regulate the magnitude of the current which is supplied to the winding when switch 15 is closed. It is usually desirable to decrease the time interval which elapses between armature movements, that is to say, increase the speed of oscillation of the armature, and winding 14 is therefore preferably connected with battery 12 in such manner that the flux which is set up in core 3 when switch 15 is closed, threads the core in the opposite direction from the resultant flux in the core due to the current supplied to windings 5 and 6. 80
- 10 15 20 25 30 35 40 45 50 55 60 65 70 75 80 85 90 95 100 105 110 115 120 125 130 135 140 145 150
- With the relay constructed in this manner it will readily be seen that if contact 13 is open when contact 15 is closed, the armature will oscillate at one speed, but that if contact 15 is closed when contact 13 is closed, the armature will then oscillate at a faster speed, the speed at which the armature oscillates in the latter case being determined for a given proportioning of the parts, by the adjustment of the variable resistor 16. 95
- It should be pointed out that the sleeve 7 is not essential to the operation of the relay, except when it is desired that the armature should oscillate at comparatively slow speeds, and it follows that if faster oscillation of the armature is desired, this sleeve may be omitted. 100
- It should be noted that when winding 14 is supplied with current in such manner that the flux set up in core 3 by this winding opposes the flux in core 3 due to the current supplied to windings 5 and 6, as shown in the drawing, then in the event that winding 14 becomes short-circuited or open-circuited for any reason, the speed of oscillation of the armature will be decreased. This is particularly desirable where the oscillation of the armature 8 is employed to actuate timing mechanism for use in railway signaling systems because damage to the winding 14 will not cause premature operation of the timing mechanism which might result in a dangerous condition. 110
- One advantage of a relay embodying our invention is that the relay may be made to operate at two different speeds without altering the arrangement or proportioning of the parts, the change in speed being effected merely by the closing of contact 15. 115
- Another advantage of a relay embodying our invention is that it is simple in construction and reliable in operation. 120
- Still another advantage of a relay embodying our invention is that the range of speed adjustment extends between wide limits. 125
- Although we have herein shown and described only one form of electrical relay embodying our invention, it is understood that various changes and modifications may be made therein within the scope of the appended claims without departing from the spirit and scope of our invention. 130
- Having thus described our invention, what we claim is:
1. A relay comprising three magnetizable cores connected together at one end by a backstrap, a first winding on a first one of said cores and a second winding on a second one of said cores, an armature pivotally attached to the third one of said cores and arranged to swing toward said first or said second core according as said first or said second winding is energized, means for alternately energizing said windings in such manner that said armature is oscillated, said windings being so arranged that the flux set up in said third core when either of said windings is energized always threads said third core in the same direction, and means for applying to said third core a magnetomotive force for controlling the resultant flux which threads said third core due to said windings. 140
2. A relay comprising three magnetizable cores connected together at one end by a backstrap, a first winding on a first one of said cores and a second winding on a second one of said cores, an armature pivotally attached to the third one of said cores and arranged to swing toward said first or said second core according as said first or said second winding is energized, means for alternately energizing said windings in such manner that said armature is oscillated, said windings being so arranged that the flux set up in said third core when either of said windings is energized always threads said third core in the same direction, a third winding on said third core, and means for supplying said third winding with current to modify the resultant flux which threads said third core due to said first and second windings. 145
3. A relay comprising three magnetizable cores connected together at one end by a backstrap, a first winding on a first one of said cores and a second winding on a second one of said cores, an armature pivotally attached to the third one of said cores and arranged to swing toward said first or said second core according as said first or said second winding is energized, means for alternately energizing said windings in such manner that said armature is oscillated, said windings being so arranged that the flux set up in said third core when either of said windings is energized always threads said third core in the same direction, a third winding on said third core, and means for supplying said third winding with current to create in said third core an additional flux which modifies the resultant flux through said third core due to said first and second windings, and means for varying the magnitude of the current supplied to said third winding. 150
4. A relay comprising three magnetizable cores connected together at one end by a backstrap, a first winding on a first one of said cores and a second winding on a second one of said cores, an armature pivotally attached to the third one of said cores and arranged to swing toward said first or said second core according as said first or said second winding is energized, means for alternately energizing said windings in such manner that said armature is oscillated, said windings being so arranged that the flux set up in said third core when either of said windings is energized always threads said third core in the same direction, and means for supplying said third core with an additional flux which opposes the resultant flux which threads said core due to said windings. 155
5. A relay comprising three magnetizable cores connected together at one end by a backstrap, a first winding on a first one of said cores and a second winding on a second one of said cores, an armature pivotally attached to the third one of said cores and arranged to swing toward said first or said second core according as said first or said second winding is energized, means for alternately energizing said windings in such manner that said armature is oscillated, said windings being so arranged that the flux set up in said third core when either of said windings is energized always threads said third core in the same direction, and means for applying to said third core a magnetomotive force for controlling the resultant flux which threads said third core due to said windings. 160

- that said armature is oscillated, said windings being so arranged that the flux set up in said third core when either of said windings is energized always threads said third core in the same 5 direction, a third winding on said third core, means for supplying said third winding with current to create in said third core an additional flux which opposes the resultant flux which threads said third core due to the energization 10 of said first and second windings, and means for varying the strength of the current supplied to said third winding to vary the magnitude of said additional flux.
6. A relay comprising three magnetizable cores 15 connected together at one end by a backstrap, a first winding on a first one of said cores and a second winding on a second one of said cores, an armature pivotally attached to the third one of said cores and arranged to swing toward said first 20 or said second core according as said first or said second winding is energized, means for alternately energizing said windings in such manner that said armature is oscillated, said windings being so arranged that the flux set up in said third 25 core when either of said windings is energized always threads said third core in the same direction, a conducting sleeve on said third core, and means for applying to said third core a magnetomotive force for controlling the resultant flux which threads said third core due to said windings.
7. A relay comprising three magnetizable cores connected together at one end by a backstrap, a first winding on a first one of said cores and a second winding on a second one of said cores, an armature pivotally attached to the third one of said cores and arranged to swing toward said first or said second core according as said first or said second winding is energized, means for alternately energizing said windings in such manner that said armature is oscillated, said windings being so arranged that the flux set up in said third core when either of said windings is energized always threads said third core in the same direction, means associated with said third core for delaying the growth and decay of the flux set up by said windings, and means for applying to said third core a magnetomotive force for controlling the resultant flux which threads said third core due to said windings.
8. A relay comprising three magnetizable cores connected together at one end by a backstrap, a first winding on a first one of said cores and a second winding on a second one of said cores, an armature pivotally attached to the third one of said cores and arranged to swing toward said first or said second core, means for supplying said first winding with current and for short-circuiting said second winding when said armature is swung toward said second core and for supplying said second winding with current and for short-circuiting said first winding when said armature is swung toward said first core whereby said armature is made to oscillate, said windings being so arranged that the flux set up by current in either of said windings always threads said third core in the same direction, and means for applying to said third core a magnetomotive force for controlling the resultant flux which threads said third core due to said windings.
9. A relay comprising three magnetizable cores connected together at one end by a backstrap, a first winding on a first one of said cores and a second winding on a second one of said cores, an armature pivotally attached to the third one of said cores and arranged to swing toward said first or said second core according as said first or said second winding is energized, means for alternately energizing said windings in such manner that said armature is oscillated, said windings being so arranged that the flux which is set up in said third core when either of said windings is energized always threads said third core in the same direction, and means for at times increasing the speed at which said armature is oscillated when said first and second windings are energized, said means comprising a third winding on said third core which is at times supplied with current in
- said cores and arranged to swing toward said first or said second core, means for supplying said first winding with current and for short-circuiting said second winding when said armature is swung toward said second core and for supplying said second winding with current and for short-circuiting said first winding when said armature is swung toward said first core whereby said armature is made to oscillate, said windings being so arranged that the flux set up by current in either of said windings always threads said third core in the same direction, a conducting sleeve on said third core for retarding the growth and decay of the flux set up by current in either of said windings, and means for applying to said third core a magnetomotive force for controlling the resultant flux which threads said third core due to said windings.
10. A relay comprising three magnetizable cores connected together at one end by a backstrap, a first winding on a first one of said cores and a second winding on a second one of said cores, an armature pivotally attached to the third one of said cores and arranged to swing toward said first or said second core, means for supplying said first winding with current and for short-circuiting said second winding when said armature is swung toward said second core and for supplying said second winding with current and for short-circuiting said first winding when said armature is swung toward said first core whereby said armature is made to oscillate, said windings being so arranged that the flux set up by current in either of said windings always threads said third core in the same direction, a conducting sleeve on said third core for retarding the growth and decay of the flux set up by current in either of said windings, and means for applying to said third core a magnetomotive force for controlling the resultant flux which threads said third core due to said windings.
11. In combination, three magnetizable cores connected together at one end by a backstrap, a first winding on a first one of said cores and a second winding on a second one of said cores, an armature pivotally attached to the third one of said cores and arranged to swing toward said first core or said second core, means for energizing said windings in such manner that said armature is oscillated, a third winding on said third core, and means for supplying said third winding with current to vary the speed at which said armature is oscillated when said first and second windings are energized.
12. In combination, three magnetizable cores connected together at one end by a backstrap, a first winding on a first one of said cores and a second winding on a second one of said cores, an armature pivotally attached to said third core and arranged to swing toward said first core or said second core according as said first or said second winding is energized, means for alternately energizing said windings in such manner that said armature is oscillated, said windings being so arranged that the flux which is set up in said third core when either of said windings is energized always threads said third core in the same direction, and means for at times increasing the speed at which said armature is oscillated when said first and second windings are energized, said means comprising a third winding on said third core which is at times supplied with current in

such manner that the flux which is set up in said third core due to current in said third winding opposes the resultant flux in said third core due to said first and second winding.

5 13. A relay comprising three magnetizable cores connected together at one end by a backstrap, a first winding on a first one of said cores and a second winding on a second one of said cores, an armature pivotally attached to the third one of
10 said cores and arranged to swing toward said first or said second core according as said first or said second winding is energized, means controlled by said armature for alternately energizing said windings in such manner that said armature is
15 oscillated, said windings being so arranged that the flux set up in said third core when either of said windings is energized always threads said third core in the same direction, and means for applying to said third core a magnetomotive force

20

for controlling the resultant flux which threads said third core due to said windings.

14. The combination with a relay having a magnetizable core, an armature, and means for supplying said core with flux to oscillate said armature, of separate and distinct means for at times applying a source of magnetomotive force to a portion of said core to vary the speed of oscillation of said armature.

15. The combination with a relay having a magnetizable core, an armature, and means for supplying said core with flux to oscillate said armature, of separate and distinct means for at times applying an additional flux to a portion of said core to vary the speed of oscillation of said armature.
